UNITED STATES PATENT OFFICE

CHARLES SEYBOLD, OF DAYTON, OHIO.

PRESS FOR EMBOSSED, &c.

SPECIFICATION forming part of Letters Patent No. 662,099, dated November 20, 1900.

Application filed January 23, 1900. Serial No. 2,492. (No model.)

To all whom it may concern:

Be it known that I, CHARLES SEYBOLD, a citizen of the United States, residing at Dayton, in the county of Montgomery and State 5 of Ohio, have invented certain new and useful Improvements in Presses for Embossing and the Like, of which the following is a full, clear, and exact description, reference being had to the accompanying drawings, forming 10 part of this specification.

My invention relates to that class of machines in which various shapes and forms are impressed or cut upon paper blanks by means of molds or dies in which the paper-stock is 15 placed between the forms and suitably embossed or cut by powerful pressure acting on the forms to bring them together, and my improvements are adapted especially to those forms of embossing and die presses in which 20 a platen is caused to descend upon the bed-plate of the machine, between which the forms and paper-stock are located, and the invention is particularly designed for embossing-presses in which it is very essential that the paper- 25 stock should be accurately fed to the forms and that the forms should be rigidly locked in exact position during the operation of the platen.

It has been frequently sought heretofore to 30 arrange some sort of automatic feed by means of which each sheet of the paper-stock might be automatically selected and fed to the press; but it has been exceedingly difficult to design such automatic feeding devices owing to the 35 difficulty of selecting one sheet at a time from a pile of sheets by mechanical means or to feed such sheet accurately to a gage when for any reason the sheets have become disarranged.

40 The usual method of feeding the press is therefore by operatives, who select the sheet by hand and place it to gage between the forms of the press. The sheet has to be placed upon the stationary bed-plate under the platen 45 in a narrow contracted space, rendering the operation both difficult to accomplish and dangerous to the operative, and as each sheet has to be thus placed and removed for each operation the movements of the machine necessarily must be slow.

In printing-presses of the bed-and-platen type it has been customary to provide an au-

tomatic shifting-plate to be moved under and away from the platen during the operation. It is not essential in such machines, however, 55 to rigidly lock the shifting-plate in position independent of the necessary lock obtained by the action of the shifting mechanism when at rest.

In my invention therefore I provide a movable platen for holding the forms which shall automatically, after each impression and while the platen is rising, slide the form from under the platen into a position readily accessible to the operative for the adjustment 60 of the paper-stock, the plate and forms to be carried back automatically under the platen and independently and rigidly locked in position for the action of the forms as soon as the platen commences to descend. In addition to this the shifting-plate is arranged to carry two sets of forms to slide out on each side of the machine, so that two operatives 65 can be employed, and the speed and capacity of the machine can thus be doubled, the details of the construction and operation of which will be hereinafter particularly pointed out and claimed.

In the drawings, Figure 1 is a rear elevation of an embossing-press with my improved 80 mechanism. Fig. 2 is a side elevation of same viewed from the left of Fig. 1, omitting the fly-wheel and pulleys. Fig. 3 is a detail side elevation of the shifting mechanism viewed from the other side. Fig. 4 is a detail 85 of the clutch for the shifting mechanism. Fig. 5 is a detail side elevation of the bed-plate. Fig. 6 is a cross-section of the bed-plate enlarged.

I have illustrated my invention in connection with a form of press such as is shown in my Patent No. 633,295, issued September 19, 1899, in which the platen is pulled down at all four corners by a system of toggles actuated by a double crank operated by heavy 90 worm-gearing, a sufficient description of which is as follows:

A is the metallic base-plate of the machine, upon which are mounted the end standards B B and crank-standards, which support the 95 bed C, all being bolted together firmly and rigidly to form a suitable framework for the working parts.

E is the platen, a substantial and massive

plate, which is hung upon the upper ends of the pulling-bars F F. H H are a pair of toggle-links, one pair for each corner, pivoted above to the framework and below to the 5 lower toggle-links L L, arranged in corresponding pairs, with their lower ends pivoted to the lower ends of the pulling-bars F F.

D D are two cross-heads pivoted to the pairs of toggle-links at their inner ends and 10 connecting the corresponding toggles on opposite sides of the machine.

The central portions of the cross-heads D D are enlarged and formed with vertical slots a a, within which the studs on the cranks M 15 engage, the studs being mounted in suitable boxes. These cranks are mounted on a crank-shaft, which carries a worm-gear O, which meshes with a worm P, mounted on the main horizontal driving-shaft R of the 20 machine. One end of this shaft carries the fly-wheel S and the usual friction-clutch pulley T, by means of which power is applied for driving the shaft R and operating the machine.

25 My improvements in the feeding mechanism for such presses, while designed for use with the general form of press above described, will be equally well adapted to other forms of die and embossing presses, and I do not 30 wish to be understood as limiting myself to the particular form of press above set forth.

A' is a plate upon which the matrix-forms for the press are mounted in the usual way. This plate is of a width to extend entirely 35 across the bed of the machine and of a length double the depth of the bed, so that when one half of the plate is under the platen the other half extends out in front or rear, so as to be readily accessible to one of the operatives 40 stationed on each side of the press. The plate is provided with a central tongue c to ride in the groove in the bed-plate B' and also with the tongues d d at the sides to ride in T-slots in the bed-plate, so that the plate A' in sliding 45 back and forth, as will be hereinafter described, will be guided accurately. The bed-plate B' is in the shape of a wedge, resting on the inclined surface of the bed-frame or table, and a screw e, taking into this bed-plate 50 B' and mounted in a box f on the bed-frame, is employed to shift the bed-plate in either direction, and thus to adjust accurately the height of the bed.

Bolted to the rear of the frame is a bracket 55 C', in which is mounted the shaft D'. This shaft carries the crank E', connected by link F' with the shifting-lever G', fulcrumed to the bracket at g. The upper end of this lever G' engages the depending lugs h at the 60 outer edge of the plate A', so that as the shaft D' is rotated with each half-revolution the lever is shifted to slide the plate A' the limit of its throw in either direction. As this movement of the plate A' is to take place only during 65 the ascending movement of the platen E, I provide as follows: Pivoted to the lug l on the side of the frame is a lever H', connected

by a link I' with the platen E. The outer end of this lever H' carries the depending rack-bar K', pivoted thereto and sliding in a guide 70 r, which rack engages the pinion L', loosely mounted on the shaft D'. Keyed on the shaft D' and abutting against the pinion is a clutch-disk M', provided on its abutting face with recesses m m to receive the spring-pressed 75 dogs n n, mounted in holes in the pinion, the dogs being pressed toward the disk M' by the spiral springs p p. These recesses m m are

beveled in one direction and form a shoulder in the other, so that the dogs will only lock 80 the pinion to the shaft-disk when the pinion is rotated from left to right, and the recesses are disposed at points substantially at right angles to the dead-center of the crank E' to allow for some rotation of the pinion L' before the disk M' and shaft D' become locked thereto. It will be evident from the above description that when the platen E and the rack-bar K' are descending the pinion L' will run free and that only after the platen has 90 started to ascend will the crank-shaft D' be rotated to actuate the lever H' to shift the matrix-carrying plate A'. In order to steady 95 the movement of the shifting-lever G', I employ a stud a' upon which to fulcrum the lever to the bracket and mount thereon a spiral spring b', bearing between the nut and washer c' and face of the lever. The nut can be adjusted to supply the proper tension upon the lever. To prevent any overthrow of the shifting-lever G', I mount on the shaft D', secured 100 to the hub of the crank E', a disk f', provided on its periphery with an ordinary spring-pressed shoe-brake g', carrying a stud h', mounted in a sleeve m' on the bracket C'. It 105 would hardly be proper, however, to rely on the mere shifting of the plate A', under the mechanism so far as described, to obtain an accurate adjustment of the embossing-forms. In a very short time the wear of the parts 110 would cause inaccuracy of throw, and in addition to this it is necessary to lock the forms rigidly in position under the enormous pressure to which they must be subjected in the process of embossing. To accomplish this 115 locking feature, I provided as follows: N' is the locking-lever, fulcrumed at s on the frame and having its lower end pivoted at t to the knuckle-joint v of one of the pair of toggles H L. The upper end of this lever has secured 120 thereto along the side of the frame and provided with a beveled edge at its extremity a sickle-bar y, held and guided under the strap u on the frame, under which the bar fits snugly. Lugs w w are provided depending 125 from the lower side edge of the plate A', one at the end of the plate and the other near the middle thereof. These lugs are so located that when the plate A' is in exactly the proper 130 position, either in or out, for the action of the dies the corresponding lugs will register exactly with the beveled end of the sickle-bar y and be engaged thereby, thus securely locking 135 the plate in position. This engagement

only takes place during the descent of the platen. As the knuckle-joint of the toggle approaches the frame of the machine the end of the sickle-bar engages the lug on the plate 5 A' and holds it locked while the platen descends. As soon as the impression has been made and the knuckle-joint of the toggle starts away from the frame the sickle-bar is at once withdrawn from its engagement with 10 the lug *w* on the plate A', and the plate is then shifted, as heretofore described, to be again locked in its other operative position. The locking-lever is released before the pinion engages the disk M' by arranging the clutch as 15 heretofore described. The end of the sickle-bar is beveled in order that proper engagement may be had should the throw of the shifting-lever G' not bring the plate A' into the exact position required.

20 The advantages of my improvements will be manifest. I automatically shift the electro-type-plate into an accessible position after each operation, and this is done first on one side and then on the other, so that by employing 25 two operatives I double the capacity of the machine.

For working the machine from both sides it is necessary to have two sets of lower forms mounted on the plate A', so that when one set 30 is being shifted into an accessible position for the operative to remove the embossing-sheet and to place a new sheet in position the other form is carried under the platen for the next operation.

35 Having thus described my invention, what I claim, and desire to secure by Letters Patent, is—

1. In a press of the character specified, provided with a platen and means for actuating 40 same, a reciprocating plate for the lower

forms, connecting mechanism intermediate said platen and plate, for shifting said plate under the back stroke of the platen, and a locking device independent of said shifting mechanism connected with said platen-actuating means to lock said plate during the forward stroke of the platen, substantially as described.

2. In a press of the character specified, the combination with the platen and mechanism 50 for actuating same, of a plate for the lower forms, shifting-lever engaging said plate, shaft carrying a crank coupled to said lever, rack-bar connected with the platen, and pinion loosely mounted on said shaft engaged by 55 said rack, with clutch between the pinion and shaft, whereby said pinion may be locked to the shaft when the movement of the rack is in one direction and may run free when the movement is in the other direction, substantially as shown and described.

3. In a press of the character specified, the combination, with a platen and pulling-bars, with toggle-levers pivoted thereto and to the frame for actuating same, of a reciprocating 65 plate for the lower forms, and connecting mechanism intermediate said plate and platen for shifting said plate, lugs on said plate and a locking-lever to engage said lugs connected with one of said toggle-levers and 70 operated thereby to lock the reciprocating plate when the toggles are moving in one direction and to release same when the toggles are moving in the other direction, substantially as shown and described.

CHARLES SEYBOLD.
